UNITED STATES PATENT OFFICE

163,709

COMBINED CUSHION AND HEADREST

Herbert S. Ray, Chicago, Ill.

Application February 27, 1950, Serial No. 8,173

Term of patent 14 years

(Cl. D15—8)

To all whom it may concern:

Be it known that I, Herbert S. Ray, a citizen of the United States, residing at Chicago, in the county of Cook and State of Illinois, have invented a new, original, and ornamental Design for a Combined Cushion and Headrest, of which the following is a specification, reference being had to the accompanying drawing, forming a part hereof.

In said drawing:

Fig. 1 is a plan view of a combined cushion and headrest, showing my new design, while

Fig. 2 is a side view thereof.

I claim:

The ornamental design for a combined cushion and headrest, as shown.

HERBERT S. RAY.
